DESIGN FOR A CIGARETTE HOLDER

Elwin L. Pickering, Los Angeles, Calif., and Clarence E. Pickering, Sr., Fort Wayne, Ind.

Application August 14, 1948, Serial No. 148,126

Term of patent 14 years

(Cl. D85—8)

To all whom it may concern:

Be it known that we, Elwin L. Pickering, and Clarence E. Pickering, Sr., citizens of the United States, and residents of the city of Los Angeles, in the county of Los Angeles and State of California, and the city of Fort Wayne, in the county of Allen and State of Indiana, respectively, have invented a new, original, and ornamental Design for a Cigarette Holder, of which the following is a specification, reference being had to the accompanying drawing, forming a part thereof.

Fig. 1 is a plan view of a cigarette holder showing our new design.

Fig. 2 is a side elevation of the cigarette holder as illustrated in Fig. 1.

Fig. 3 is an end elevation of the cigarette holder as viewed from the left side of Fig. 2.

Fig. 4 is a perspective of the cigarette holder.
We claim:

The ornamental design for a cigarette holder, as shown.

ELWIN L. PICKERING.
CLARENCE E. PICKERING, SR.
